D11-4. OR D11,237 EX

DESIGN FOR BRACELET.

Specification forming part of Design No. **11,237**, dated June 10, 1879; application filed May 5, 1879.
[Term of patent 3½ years.]

UNITED STATES PATENT OFFICE

HERMAN UNGER, OF NEWARK, NEW JERSEY, ASSIGNOR TO FREDERICK UNGER AND EUGENE UNGER, OF SAME PLACE, ONE-THIRD TO EACH.

DESIGN FOR BRACELET.

Specification forming part of Design No. **11,237**, dated June 10, 1879; application filed May 5, 1879.
[Term of patent 3½ years.]

To all whom it may concern:

Be it known that I, HERMAN UNGER, of the city of Newark, in the county of Essex and State of New Jersey, have originated a new Design for a Lady's Bracelet, of which the following is a full, clear, and exact description, reference being had to the accompanying photographic illustration, making part of this specification.

In the drawing, A represents the body of the bracelet, which, in this instance, is composed of black onyx, and B indicates the ornament, which represents a lily-of-the-valley spray made in gold and set with pearls, thus producing, by the contrast in the colors, a very beautiful effect.

I do not limit myself, however, to the materials herein designated of which the article is composed; but

What I claim as my invention is—

The design for a bracelet, consisting of the body A and the ornamental representation of a lily-of-the-valley spray, substantially as described, and shown in the accompanying drawing.

In testimony that I claim the foregoing I hereunto set my hand in presence of two witnesses.

HERMAN UNGER.

Witnesses:

OLIVER DRAKE,
CHARLES H. PELL.
